[57] CLAIM

The ornamental design for a desk top connector, as shown and described.

DESCRIPTION

FIG. 1 is a perspective view of a desk top connector, showing our new design, the broken lines are for illustrative purposes only;

FIG. 2 is a top plan view;

FIG. 3 is a side elevational view, taken from the left of FIG. 2; and,

FIG. 4 is a side elevational view, taken from the bottom of FIG. 2 thereof.

FIGS. 2-4 have been drawn on an enlarged scale with respect to FIG. 1.

FIG. 4
